DESCRIPTION

FIG. 1 is a perspective view illustrating my design for a waistband pack with the ends thereof engaged.

FIG. 2 is a front perspective view with the ends thereof disengaged.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

The broken straight line illustrated in FIGS. 1 through 6 represent a seam which is not part of the claimed design and is presented for illustrative purposes only. Furthermore, the zipper clasps or handles illustrated in FIGS. 1 through 8 are also presented in broken lines, and thus form no part of the claimed design.
